US00D958735S

(12) **United States Design Patent** (10) **Patent No.:** **US D958,735 S**
Perkins et al. (45) **Date of Patent:** **** Jul. 26, 2022**

(54) **CHARGER**

(71) Applicant: **Welch Allyn, Inc.**, Skaneateles Falls, NY (US)

(72) Inventors: **David G. Perkins**, Tully, NY (US); **Sean R. Karla**, Camillus, NY (US); **Timothy R. Fitch**, Syracuse, NY (US); **David M. Villarreal**, Fayetteville, NY (US); **Michael Suits**, Camillus, NY (US); **Timothy Braun**, Auburn, NY (US); **Robert S. Englert**, Syracuse, NY (US)

(73) Assignee: **WELCH ALLYN, INC.**, Skaneateles Falls, NY (US)

(**) Term: **15 Years**

(21) Appl. No.: **29/795,982**

(22) Filed: **Jun. 22, 2021**

Related U.S. Application Data

(63) Continuation of application No. 29/729,228, filed on Mar. 25, 2020, now Pat. No. Des. 926,128.

(57) **CLAIM**

We claim the ornamental design for a charger, as shown and described.

DESCRIPTION

FIG. 1 is a perspective view of a charger showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a left side elevation cross-section view thereof taken along line 8-8 in FIG. 6; and,

FIG. 9 is a front elevation cross-section view thereof taken along line 9-9 in FIG. 6.

The broken lines illustrate features of the charger that form no part of the claimed design.

1 Claim, 5 Drawing Sheets
